UNITED STATES PATENT OFFICE.

HERBERT O. RUSSELL, OF DETROIT, MICHIGAN, AND CHARLES LEIGH PAULUS, OF DAYTON, OHIO.

ELECTRICALLY-OPERATED WING-TIP FLARE BRACKET.

Application filed April 18, 1922. Serial No. 555,403.

This invention relates to electrically operated wing tip flare brackets, the object in view being to provide a mechanism to replace the Holt wing tip flare bracket and at the same time provide means whereby the flare bracket may be held out of the air stream when not in use. This apparatus is designed to be used in connection with the flare holder and tip, such as is described and claimed in my copending application Serial Number 555,406.

With the above and other objects in view, the invention consists in the novel construction, combination and arrangement herein fully described, illustrated and claimed.

In the accompanying drawings:

Fig. 1 is a plan view of the device;

Fig. 2 is a view partly in side elevation and partly in section of the device showing the same in its folded or horizontal position.

Fig. 3 is an end view thereof.

Referring to the drawings, 1 designates a mounting bracket adapted to be secured to an aircraft and particularly designed to be fastened to the under side of one of the wings of an airplane.

Connected to the bracket 1 by means of a pivot 2 is a flare carrying arm 3 having at its outer end a housing 4. The housing 4 contains a candle ejecting spring 5 which is under compression when the candle 6 is in place. The candle 6 is held by means of a clamping band 7 controlled and adapted to be relaxed by a trip arm 8 when the latter strikes against the ground. The end portions 9 of the clamping band 7 are held in clamping position by means of a cam 10 on one of the end portions of said band and a cooperating cam 11 on the adjacent end of the trip arm 8.

Extending from the upper or inner end of the housing 4 is a spring actuated thrust member 12 in the form of a bar or rod having one end connected to the mounting bracket 1 by means of a pivot 13 off-set from the pivot 2 of the arm 3. The spring 5 acts against the adjacent end of the thrust member 12 so that when the device is released, the spring 5 serves to throw the mechanism from the substantially horizontal carrying position shown in Figure 1, to a substantially vertical or pendent position.

The means for holding and releasing the mechanism above described embodies a catch

14 engaging a keeper 15 on the thrust member 12 as shown in Figure 1. The catch 14 is maintained in engagement with the keeper 15 by means of a spring 16. The catch 14 carries an armature 17 adapted to be attracted by the core 18 of an electromagnet 19.

At one end of the arm 3 is a contact 20 which, when the arm 3 drops to a substantially vertical position, rests against another contact 21. The contacts 20 and 21 are in circuit with a battery 22 or other source of electrical energy controlled by a push button or switch 23. Suitable terminals 22 and 23' are provided on the arm 12 adapted to receive and frictionally hold the ends of the two wires 24 and 25 with which such candles are provided and by means of which the candles are ignited. The purpose of having these wires thus frictionally held in position in their terminals is that the flare candles will thus fall freely under the action of the spring in the case when the release or trip lever strikes the ground. It will be noted that one lead from the candle is grounded at the terminals on the arm 12 and that one side of the switch at the battery is grounded on the bracket 1 so that when the switch 23 for the battery is closed, the solenoid 19, one end of the coil of which also is grounded, attracts the armature 14 and allows the flare candle to swing downwardly until the contacts 20 and 21 engage. A circuit through the flare candle is then completed in an obvious manner. When the mechanism is not in its position of use it is held up in a substantially horizontal position so as to reduce head resistance to a minimum.

Having thus described our invention, we claim:

1. The combination of a supporting bracket, a flare candle housing, a supporting arm for said housing connected by a pivot to said bracket and adapted to swing from its normal carrying position to its operative position, a spring-actuated thrust member acting to move said arm to its operative position and connected to the bracket by a pivot offset from the pivot of said arm, and means for holding and releasing said arm and thrust member.

2. The combination of a supporting bracket, a flare candle housing, a supporting

2
arm for said housing connected by a pivot to said bracket and adapted to swing from its normal carrying position to its operative position, a spring-actuated thrust member 5 acting to move said arm to its operative position and connected to the bracket by a pivot offset from the pivot of said arm, and means for holding and releasing said arm and thrust member, and electromagnetically controlled means for igniting the flare candle, the last named means being thrown into action when the arm swings to its operative position.

3. In combination with a supporting 15 means a flare holding member, means for releasably retaining the flare holding member in one position relative to the supporting means and means for moving the flare holding member to a second position relative to 20 the supporting means.

4. In combination with a supporting means, a movable flare holding member, electrical means for igniting a flare in the holding member including a switch closed only

when the flare holding member is in one position relative to the supporting member. 25

5. In combination with a supporting means, a movable flare retaining member, an electromagnetically controlled means for releasably retaining the flare retaining member in one position relative to the supporting means and spring actuated means for moving said flare retaining member to a second position relative to the supporting means. 30

6. In combination with an aerofoil of an aircraft, a flare holding member pivotally carried by the under surface of the aerofoil, means for releasably holding the flare retaining member in a substantially horizontal position and means to move said flare holding member to a substantially vertical position when the flare holding member is released by said first mentioned means. 35 40

In testimony whereof we affix our signatures.

HERBERT O. RUSSELL.
